UNITED STATES PATENT OFFICE

STANLEY P. LOVELL, OF NEWTON, MASSACHUSETTS, ASSIGNOR TO ARDEN BOX TOE COMPANY, OF WATERTOWN, MASSACHUSETTS, A CORPORATION OF MASSACHUSETTS

SHOE STIFFENER

Original application filed May 20, 1929, Serial No. 364,413. Divided and this application filed May 27, 1930. Serial No. 456,045.

This invention relates to stiffeners, more particularly for the toe portions of shoes and of that type wherein the stiffeners reach the shoemaker in softened condition ready for incorporation directly into shoes and for lasting without preliminary conditioning treatment. The stiffening agent for imparting stiffness to stiffeners of this type is one which is softened by a solvent, usually non-aqueous, and which evaporates after the stiffener is exposed to the air, and in order that the stiffeners may be in proper condition for the shoe manufacturer, they are packed in hermetically sealed containers which prevent evaporation of the solvent until it is desired to use them at the shoe factory when the container is opened.

More specifically the present invention relates to a stiffener, more especially adapted for use in the manufacture of turn shoes, and wherein an external face of the stiffener is in tacky condition when it is assembled in the shoe so that it may adhere firmly to the adjacent shoe part or parts so as to permit turning of the shoe after lasting without displacing the stiffener. This application is a division of my application Serial No. 364,413, filed May 20, 1929, for Shoe stiffeners and method and means for packaging and handling the same.

In accordance with this invention the stiffener is preferably made with one or more layers of fabric, preferably two layers, each of which is coated on one or both faces with a suitable stiffening agent softenable with a volatile solvent. The stiffeners after treatment with the solvent are then stacked between protective separator sheets to which they do not strongly adhere and the separator sheets are so formed as to facilitate the placing of the stiffeners in assembled relation in shoes.

While this invention is not limited thereto, a stiffening agent which has been found very satisfactory is an ester of cellulose. By proper choice of the volatile solvent used, it is possible to control the time of hardening of the stiffener after it has been removed from its container, this time of hardening being predetermined in accordance with the

character of the shoes being made and with particular relation to the particular problems and equipment of the individual shoe factory.

For a more complete understanding of this invention, reference may be had to the accompanying drawings in which

Figure 1 is a plan of a separator sheet prepared to receive a treated stiffener prior to packaging.

Figure 2 is a plan showing a treated stiffener in place on the separator sheet.

Figure 3 shows in perspective a stack of stiffeners and interposed separator sheets showing in dotted lines the manner in which the stiffeners can be removed successively from the stack for use.

Figures 4 and 5 are sections through a stiffener and separator sheet showing successive stages in the removal of the stiffener from the sheet.

Referring to the drawings, 1 indicates a shoe stiffener, such for example as a box toe, which is composed of one or more plies of fabric as 2 and 3 which are coated on one or both faces (preferably both) with a suitable solvent-softened stiffening agent, such, for example, as an ester of cellulose as at 4. This coating is preferably applied to the fabric before it is died out into stiffener blanks, and where two or more plies are employed, one at least of these plies is preferably somewhat larger than the others in order to form a marginal extension 5, particularly along the rear edge of the toe stiffener to present a thin edge, thus eliminating the necessity of skiving the completed stiffener to produce this desired thin edge which tends to avoid a visible line of demarcation between the stiffened and unstiffened portions of the completed shoe.

When the stiffeners are being prepared, the blanks cut from the coated material are dipped into a suitable solvent for the particular stiffening agent employed, and preferably this is a non-aqueous volatile solvent which is so constituted that the time of setting of a stiffener softened by its use when the stiffener is exposed to the air may be predetermined within reasonably close limits to conform to the requirements of the particular shoe fac-

tory in which the shoes are to be made. A particularly suitable stiffening material is an ester of cellulose and the particular solvents which may be employed may vary considerably. Certain examples of such solvents are denatured alcohol, acetone, glycol ester derivatives such as diethylene, glycol monomethyl ether, ethylene, glycolmonobutyl ether and ethyl acetate. The denatured alcohol and acetone are solvents which cause a very short time of setting, while the glycol ester derivatives are slow in their action. The ethyl acetate is fast, but leaves an odor which in some cases may be objectionable. By properly combining these or other solvents, the time of setting of the stiffening agent may be quite accurately predetermined from a few minutes to several hours.

Where more than one ply is used, both plies are dipped in the desired solvent and are then assembled in face to face relation, leaving the desired overlap about the margin, on a separator layer or sheet 6 to which the softened stiffening agent will not strongly adhere, such, for example, as a sheet of waxed paper which is thin, non-absorbent and substantially unaffected by the solvents. When a blank is dipped the solvent is immediately absorbed by the fabric base and attacks the stiffening agent, which, after it has been acted on for a sufficient length of time, is softened to a tacky condition. After a stiffener has been thus dipped and laid on a separator sheet 6, another separator sheet is laid thereon and another stiffener is dipped and assembled on the second separator sheet, this process being carried on until a stack of alternate stiffeners and separator sheets has been made to the desired number of stiffeners. The stack is then placed in a suitable container which may be hermetically sealed to avoid the evaporation of solvent and to permit the stiffening agent to soften and reach its desired tacky condition.

When it is desired to use the stiffeners the container is opened and the stiffeners are pulled away one after another from their separator layers and placed in position in the shoes with the tacky face or faces against the desired shoe part or parts to which they immediately adhere. In order to facilitate the removal of the individual stiffeners from the separator sheets and their assembly in the shoes without danger of injuring the tacky surface or soiling the fingers or shoe parts with the tacky material, each of the separator sheets may be provided with a portion such as 16, defined by weakened portions or partial cuts as at 17 from the remainder of the sheet so that the shoe operative can fold one part of the weakened portion over the edge of the stiffener, as shown in Figure 4, thus to form with the remainder of the portion 16 a non-sticky finger hold at the stiffener edge. This may be grasped between the

operator's fingers and by pulling the portion 16 may be entirely detached from the separator sheet, as shown in Figure 5 and in dotted lines in Figure 3, whereupon the stiffener may be readily peeled off from the separator sheet and applied to the shoe in proper position without the fingers touching any portion of the tacky surface and without any contact between this surface with other parts of the shoe or with the operator's clothing. Where the portion 16 is applied to the margin of the stiffener which is lasted in during the lasting operation, no difficulty is experienced by reason of the fact that this portion of the stiffener will not adhere to the shoe. Hence it is quite unnecessary to remove the portion 16 from the stiffener.

The external coating of stiffening agent is acted on by the solvent while in contact with the separator layer and this layer has the effect to cause the surface coating when in softened condition to be of a jelly like consistency which condition adapts the stiffener admirably for immediate application to a shoe.

Certain embodiments of this invention having been thus described, it should be evident to those skilled in the art that various changes and modifications might be made therein without departing from the spirit or scope of this invention as defined by the appended claims.

I claim:

1. A shoe stiffener prepared for assembly in a shoe and comprising one or more fabric plies, and having an external face coating of a normally solid stiffening agent in a plastic tacky condition. 100
2. A shoe stiffener prepared for assembly in a shoe and comprising one or more fabric plies, and having an external face coating of a normally solid solvent-softened stiffening agent pre-treated with the solvent and in a plastic tacky condition. 105
3. A shoe stiffener prepared for assembly in a shoe and comprising one or more fabric plies, each ply having a surface coating of a normally solid stiffening agent in a plastic tacky condition, at least one of said coatings being on one external face of the stiffener. 110
4. A shoe stiffener prepared for assembly in a shoe and comprising one or more fabric plies, each ply having a surface coating of a normally solid solvent-softened stiffener agent pre-treated with the solvent and in a plastic tacky condition, at least one of said coatings being on one external face of the stiffener. 115
5. A shoe stiffener prepared for assembly in a shoe and comprising one or more fabric plies, each ply having a surface coating of an ester of cellulose in a plastic tacky condition, at least one of said coatings being on one external face of the stiffener. 120
6. A shoe stiffener prepared for assembly 125

in a shoe and comprising one or more fabric plies coated on both faces with a normally solid stiffening agent in a plastic tacky condition.

7. A shoe stiffener prepared for assembly in a shoe and comprising one or more fabric plies coated on both faces with an ester of cellulose in a plastic tacky condition.

In testimony whereof I have affixed my signature.

STANLEY P. LOVELL.
